UNITED STATES PATENT OFFICE.

CHARLES O. SOBINSKI, OF ST. LOUIS, MISSOURI.

AIR PUMP OR COMPRESSOR.

SPECIFICATION forming part of Letters Patent No. 630,525, dated August 8, 1899.

Application filed April 2, 1897. Serial No. 630,427. (No model.)

To all whom it may concern:

Be it known that I, CHARLES O. SOBINSKI, a citizen of the United States, residing at St. Louis, State of Missouri, have invented certain new and useful Improvements in Air Pumps or Compressors, of which the following is a full, clear, and exact description, reference being had to the accompanying drawings, forming a part hereof.

My invention has relation to improvements in air pumps or compressors; and it consists in the novel arrangement and combination of parts more fully set forth in the specification and pointed out in the claims.

In the drawings, Figure 1 is a part elevation of my invention and part section, taken on the line xx of Fig. 2. Fig. 2 is a top plan view with the air outlet or escape pipe removed. Fig. 3 is a plan detail of one of the cam-plates along which the dogs travel. Fig. 4 is a detail elevation and middle section, respectively, of the reciprocating pistons. Fig. 5 is a plan view of one of the pistons. Fig. 6 is a detail of the packing and flap-valves cut therefrom. Fig. 7 is a perspective detail of the plate, corresponding to the cross-head of the ordinary engine, attached to the solid piston-rod. Fig. 8 is a perspective of the dog mounted thereon. Fig. 9 is a sectional detail on yy of Fig. 1. Fig. 10 is a sectional detail on zz of Fig. 1, with the disk of the driving-shaft turned a quarter-revolution from the position shown in Fig. 1. Fig. 11 is a longitudinal section of the plate carried by the solid piston-rod. Fig. 12 is a similar section of the plate attached to the hollow piston-rod. Fig. 13 is a detail elevation showing the application of a rock-shaft instead of a revolving drive-shaft. Fig. 14 is a detail plan of the same. Fig. 15 is a detail of the crank-arms carried by the rock-shaft. Figs. 16 and 17 are detail plan views of the plates carried by the piston-rods of said modified form of pump.

The object of my invention is to construct an air pump or compressor which for a given stroke of piston will control a maximum volume of air, the present device comprising as an essential feature two pistons operating simultaneously in a single cylinder and suitable inlet and outlet ports disposed on each side of each piston, whereby the efficiency of

the pump is raised to a point unattained, so far as I am aware, by any of the existing and prevailing forms of pumps. The present 55 pump is operated from a single rotating or oscillating shaft, the mechanical connections between said shaft and the pistons being such as to produce a compactness of structure differing essentially from any other device of a 60 similar nature. Although specifically denominated an "air-pump," it will be apparent that the same may operate on water or other fluid. In detail it may be described as follows:

Referring to the drawings, Figs. 1 and 2, it will be observed that I have shown two sets of cylinders, one on either side of a central operating-shaft, the parts on one side being mere duplicates of the counterparts on the 70 opposite side, so that a description of one half of the machine will answer for the corresponding parts of the opposite half. The pump is provided with the usual cylinder 1, in which operate the pistons 2 and 3, the hollow piston-rod 4 of the former loosely receiving the solid piston-rod 5 of the latter, the piston-rods both 75 extending in the same direction toward the main drive-shaft 6, operated by a pulley 7 from any suitable source of power. (Not 80 shown.) Both pistons are reciprocated by the rotation of the shaft 6. The latter is mounted in suitable bearings 8, whose flanged portions 8' are secured to the lateral walls or plates 9, by which the cylinders 1 1 of the 85 double machine are united. For the sake of lightness of construction the plates 9 (which for reasons to appear subsequently are denominated as the "cam-plates") are cut away, the cut-away portion being covered 90 by a thin plate 10 to insure rigidity for the parts. Formed integrally with the flanged portions 8', along the inner surface thereof and about the opening through which the operating-shaft passes, is an offset 11 of peculiar polygonal contour, (see Fig. 3,) which passes through a larger opening of similar contour formed in the cam-plate 9, the outer edges of said offset and the inner walls of the opening forming jointly when the parts are 100 assembled suitable cam-slots 12 around the shaft 6 along each wall or plate 9. The hollow piston-rod terminates in an offset 13, with which is formed integrally a plate 14, con-

necting together the hollow piston-rods of the double machine, said plate being provided with a longitudinal slot or cut-away portion 15, elongated in the direction of the piston-rod and adapted to embrace the operating or drive shaft 6, the plate 14 being located adjacent to the inner wall of the cam-plate on that side of the machine. The connection between the adjacent ends of the hollow piston-rods is further strengthened by a longitudinally-slotted stiffening bar or plate 16, located adjacent to the inner surface of the opposite cam-plate 9. (See Fig. 10.) Connecting the adjacent ends of the solid piston-rods 5, projecting from the hollow piston-rods within which they operate, is a plate 17, provided with a similarly-elongated opening 18, embracing the drive-shaft, and carried by the drive-shaft 6 and interposed between the plates 14 and 17 is a disk 20, having located on opposite faces thereof and at points diametrically removed from each other antifriction-rollers 21, whose purpose will be presently described.

Intersecting at right angles the slot 15, along the inner face of the plate 14 and disposed medially the length of the slot on each side of the same, is a transverse guideway or groove 22, and similarly intersecting the slot 18 of the plate 17 is a similar groove 22', the adjacent ends of the grooves terminating in reduced pockets 23 23', cut in the respective plates. Adapted to be guided between the lateral walls of each groove 22 22' is a dog 24, provided with a longitudinal slot or guideway 25, each dog when inserted into its groove 22 (or 22') being flush with the inner surface of the plate by which it is carried. The inner end of that wall of each dog which is directly supported by the base of the groove 22 is provided with a laterally-projecting lug 26, which is of such dimensions that when the dogs have been forced apart toward the bases of the grooves, as subsequently to be explained, it (the lug) completely fills the pocket 23 at the free end of the groove and comes flush or is continuous with the lateral wall of the slot 15 or 18. (See Fig. 1.) The lug 26 is provided with a pin 27, which is designed to travel in the cam-slot 12 and guide the dog in the path of the slot, as presently to be explained. By way of distinction the dog carried by the plate 17 is lettered 24', its slot 25', and lug 26', and pin 27', this distinction resulting from the fact that the lug 26' is deeper than the lug 26, as the former is extended to pass the thickness of the stiffening-bar 16 to reach the adjacent surface of the cam-plate on that side, the bar 16 having a cut-away portion 28 to accommodate the parts. By reason of the increased depth of the lug 26' the lateral walls of the pocket 23, which receives it, are correspondingly lengthened by providing the plate 17 with an offset or shoulder 29, (see Fig. 7,) in which said pocket is cut, the base of the lug 26' and the offset 29 normally bearing against the inner surface of the cam-plate in the cam-slots of which the

pin 27' operates. The rollers 21, carried by the disk 20 of the drive-shaft, freely operate in the slots 25 25' of the dogs, and each dog 70 in its travel along the cam-slot is guided and kept true to its position in its groove 22 or 22' by a rear terminal guide-pin 30 30', passing through a suitable opening 31 or 31, formed in the plates 14 17 at the bases of the 75 guideways or grooves 22 22', respectively.

The operation of the device is as follows: It is obvious that as the pistons 2 3 are reciprocated to and from each other the plates 14 17 will be correspondingly reciprocated and the 80 dogs carried by and guided in the grooves 22 22' of said plates will also be reciprocated; but in the reciprocation of the dogs the latter are compelled to follow in the path of the cam-slots 12, bringing the adjacent ends of 85 the dogs together at the limit of each stroke and gradually forcing the dogs apart as they approach the medial or basal portions of the cam-slots. The foregoing merely describes the path taken by the dogs during the reciprocation of the pistons; but in reality it is through the dogs that motion is imparted to the pistons. This is accomplished as follows: Each roller 21 of the disk 20 is adapted to operate in the slot 25 25' of the dogs. It may 90 be stated in passing that each groove 22 22' is of sufficient length to allow the dog to play in the groove a distance equal to the perpendicular distance between a line joining the free opposite ends of the cam-slot and the base or 100 medial portion of said slot, and, furthermore, that the length of each slot 25 25' is such as to allow for the free and uninterrupted passage through it of the rollers 21 during the rotation of the disk 20—that is to say, when the 105 dogs occupy a position along the medial portion of each cam-slot 12 each roller will be approximately at the base of the slot formed in the dog. (See Fig. 1.) Now as rotation is imparted to the shaft 6 from any source of 110 power it follows that the disk 20 will be rotated. As the disk 20 rotates the rollers 21 thereof, operating as they do within the slots 25 25' of the dogs, will carry the latter with them; but as the dogs cannot describe a circular path (not being pivotally connected to the rollers) they are obliged to travel along the cam-slots 12 to allow of a free and uninterrupted rotation of the driving-disk 20. The disk with its two diametrically opposite located rollers 21 acts as two crank-arms, each crank-arm during its rotation driving before it one dog of each pair at a time, the other dog of each pair, mounted on the plates 14 17, being carried along bodily by the plate to which 120 it is attached until the pistons have each reached the limit of their respective strokes, when the next dog of each pair will be positively driven by the crank-arms. Each pair of dogs, it will be remembered, come together 125 at the limit of each stroke of each piston, thus (by their slots 25 25', as seen by the dotted lines in Fig. 4) forming a continuous guideway for the roller 21, enabling the lat-

ter without interruption to freely pass from the slot of one dog to that of the adjacent dog and drive the particular plate carrying the same in the reverse direction. By the construction described the stroke of either piston corresponds to the full length or distance between the rollers 21, carried by the disk 20, and the device has the advantage of being compact and occupying less room than were the piston-rods pivotally connected to the disk 20 and their respective pistons, as is usual where curvilinear motion is converted into rectilinear motion. Under the present construction the circular motion or component of the reciprocating piston-rods is assumed by the dogs. As seen from Fig. 1, when the crank-arms at whose free ends the rollers 21 are supposed to be mounted are disposed vertically the pistons 2 3 occupy a normal position. When the disk 20, however, has made a quarter-revolution, the relative positions of the plates 14 17 and dogs carried by them will be such as to drive each pair of dogs to the limits or adjacent ends of the cam-slots 12—that is, the pistons will have reached the limits of their outward strokes and thus be forced away from each other. (See extreme dotted positions in Fig. 1.) When the disk 20 has made a second quarter-revolution, the parts will again occupy the position shown by solid lines in Fig. 1. At the next or third quarter of a revolution they will be forced toward their inner limit, (see inner dotted position of the pistons in Fig. 1,) never passing, however, the inlet and outlet ports with which the cylinder-wall is provided and to which reference will presently be made. At the fourth quarter of a revolution they will again occupy their normal position. The pistons of course reciprocate simultaneously in opposite directions within the same cylinder, being driven by a single drive-shaft 6, the entire length of piston-rod reciprocating along a rectilinear line, the circular component of the motion imparted by the disk 20 being taken up by the dogs, as already described. The piston-rod 4 passes through a suitable stuffing-box at the end of the cylinder.

Disposed along the cylinder-wall are a series of air-inlet compartments 32, a port 33 leading from each to the cylinder and disposed on each side of each piston in any of its extreme positions, each compartment being controlled by an inwardly-opening flap-valve 34, weighted by a plate 35, said valve being formed by cutting the flap from a sheet of leather packing 34, covering the several compartments 32, the flap closing against the inner wall of an air-chamber 36, leading from the common inlet pipe or duct 37. Corresponding in position to the air-inlet ports 33 are the outlet-ports or discharge-openings 38, controlled by flap-valves 39, constructed similarly to the previous valves and opening into an air-ducting pipe or chamber 40, leading to a discharge-opening 41. It will be observed that the several pairs of inlet and cor-

responding outlet openings or ports are disposed in planes parallel to the faces of the reciprocating pistons. With each joint reciprocation of the pistons it is apparent that either air will be admitted through the center port 33 between the pistons and simultaneously ejected from the extreme discharge-ports 38 or air will be admitted through the extreme inlet-ports 33 on top of each piston and simultaneously discharged through the middle discharge-port 38, thus at all times pumping a maximum volume of air. It is of course apparent that water or any other fluid could be pumped with the same device.

To insure a tight joint between the pistons and the inner wall of the cylinder, I secure to the outer peripheral rim or ledge 42 of each piston (see Fig. 4) a trough-shaped annular packing-ring 43 on each face of the rim, securing the packing-rings by annular plates 44, connected to the rim by bolts 45.

In Figs. 13 to 17 I have shown a modified form of driving mechanism. The shaft 6 instead of being provided with a disk 20 is provided with two crank-arms 20', each carrying on opposite sides antifriction-rollers 21. These rollers operate in the lateral recesses 50, cut in the plates 51 52, attached, respectively, to the solid and hollow piston-rods and corresponding to the plates 17 14 already described, each recess communicating with the longitudinal slot 15' and 18' cut in said plates. To the pin 53 of each roller may be secured a rod or bar 54, whereby the crank-arms 20' can be rocked or oscillated, in this way oscillating the plates 51 52 and the piston-rods of which they form a part, and thereby reciprocating the pistons as if a complete revolution of the crank-arms took place. This modification I illustrate merely to show the possibility of reciprocating the pistons by the mere oscillation of rocking of the crank-arms and shaft 6' to which they are secured without a complete revolution of such shaft. It is obvious that many other minor changes could be made without departing from the spirit of my invention.

By disposing the several air-inlet compartments 32 along the peripheral wall of the cylinder and locating the valves 34 in a position to simultaneously communicate with a common inlet pipe or duct, as described, the present apparatus can be conveniently converted from a compressing-pump to a vacuum-pump, as is obvious.

Having described my invention, what I claim is—

1. An air-pump comprising two sets of cylinders, a central operating-shaft disposed transversely to the axes of the cylinders between their contiguous or adjacent ends, two oppositely-reciprocating pistons operating in each cylinder, the piston-rods of the several pistons extending from each cylinder toward the common operating-shaft, and the rod of one piston being hollow to receive the rod of the other piston, air-inlet and air-discharge

openings or ports formed in, or leading from the peripheral walls of the cylinders on each side of each piston, the air-inlet ports on either side of each piston having their corresponding air-discharge ports located in like relation to said piston, a series of independent valve-controlled compartments disposed along the peripheral wall of each cylinder, each compartment communicating with an air-inlet port, and a valve for each discharge opening or port, the latter communicating with a common ejection pipe or chamber, and the parts operating substantially as and for the purpose set forth.

15 2. In an air pump or compressor, a cylinder, a piston and piston-rod therefor, a drive-shaft, a suitable dog in connection with the piston

having a longitudinal slot, a lug projecting from one end of one of the longitudinal surfaces of the dog, a pin carried by the lug, a guide-pin projecting longitudinally the length of the dog and projecting from one end of the same for guiding the dog, cam-slots for the travel of the pin carried by the lug, and intermediate connections between the dog and the drive-shaft for actuating the former and reciprocating the piston upon rotation of the drive-shaft, substantially as set forth.

In testimony whereof I affix my signature in presence of two witnesses.

CHAS. O. SOBINSKI.
